DESIGN FOR A GAME BOARD

William C. Wymer, United States Navy,
Oregon City, Oreg.

Application September 20, 1945, Serial No. 122,193

Term of patent 3½ years

(Cl. D34—5)

To all whom it may concern:

Be it known that I, William C. Wymer, a citizen of the United States and an officer of the United States Naval Reserve on active duty, residing at Oregon City, in the county of Clackamas and State of Oregon, have invented a new, original, and ornamental Design for Game Boards, of which the following is a specification, reference being had to the accompanying drawing, forming part thereof.

The figure is a plan view of a game board, showing my new design.

The game board is of conventional thickness.

I claim:

The ornamental design for a game board, substantially as shown and described.

WILLIAM C. WYMER.
